UNITED STATES PATENT OFFICE.

WALTER DORWIN TEAGUE, OF NEW YORK, N. Y., ASSIGNOR TO THE J. B. WILLIAMS COMPANY, OF GLASTONBURY, CONNECTICUT, A CORPORATION OF CONNECTICUT.

DESIGN FOR A LABEL-BLANK.

41,978.

Specification for Design.

Patented Dec. 12, 1911.

Application filed August 16, 1911. Serial No. 644,481. Term of patent 14 years.

To all whom it may concern:

Be it known that I, WALTER DORWIN TEAGUE, a citizen of the United States, residing at New York, in the county and State of New York, have invented a new, original, and ornamental Design for a Label-Blank, of which the following is a specification, reference being had to the accompanying drawing, forming part thereof.

The figure is a view of one-half of a label blank showing my new design, the other half being a reproduction of that shown.

I claim—

The ornamental design for a label blank, as shown.

WALTER DORWIN TEAGUE.
